(57) **CLAIM**

The ornamental design for a shower enclosure, as shown and described.

DESCRIPTION

In a preferred embodiment, the nature of this product is as a shower enclosure, which is primarily useful for washing humans.

FIG. 1 is a top, left, front perspective view of a shower enclosure embodying my new design;

FIG. 2 is a front elevational view thereof;

FIG. 3 is a left side elevational view thereof, the right side elevational view thereof being a mirror image of the left side shown;

FIG. 4 is a top plan view thereof;

FIG. 5 is a bottom plan view thereof;

FIG. 6 is a rear elevational view thereof;

FIG. 7 is a top, left, front perspective view of a shower enclosure according to another embodiment of my new design;

FIG. 8 is a front elevational view thereof;

FIG. 9 is a left side elevational view thereof, the right side elevational view thereof being a mirror image of the left side shown;

FIG. 10 is a top plan view thereof;

FIG. 11 is a bottom plan view thereof; and,

FIG. 12 is a rear elevational view thereof.

The broken line representations of wall seams, flange structure, a drain and/or shelving in the figures are for the purpose of illustration only, and form no part of the claimed design.
